Primary Examiner — Sandra Snapp*Assistant Examiner* — Dustin Andrew Griffith(74) *Attorney, Agent, or Firm* — Sandy Lipkin(57) **CLAIM**

The ornamental design for a golf bag divider top, as shown and described.

DESCRIPTION

FIG. 1 is a perspective view of a golf bag divider top showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is bottom plan view thereof.

The broken lines in the drawings depict portions of the golf bag divider top that form no part of the claimed design.
